UNITED STATES PATENT OFFICE.

WILLIAM WERNER AND JOHN CURRIVAN, OF BROOKLYN, NEW YORK.

ACCORDION-DOOR.

1,043,492.

Specification of Letters Patent.

Patented Nov. 5, 1912.

Application filed October 20, 1911. Serial No. 655,801.

To all whom it may concern:

Be it known that we, WILLIAM WERNER and JOHN CURRIVAN, citizens of the United States, residing at Brooklyn, in the county of Kings and State of New York, have invented certain new and useful Improvements in Accordion-Doors, of which the following is a specification.

The present invention is an improved accordion door and relates to improved means for supporting and operating such doors.

In the drawings which show one of the specific embodiments which the invention may take, Figure 1 is a front elevation of the improved door embodying the invention showing parts of the devices broken away to reveal internal structure; Fig. 2 is a vertical section on the line 2—2 in Fig. 1 looking in the direction of the arrows, said section being on an enlarged scale and the middle portion of the door being broken out and omitted for the sake of compactness; Fig. 3 is a view of the same parts as in Fig. 2 except that the view is a side elevation partly in section looking at the right hand side of the devices in Fig. 2; and Fig. 4 is a plan view on an enlarged scale of portions of the devices of Fig. 1 showing the doors in folded-up position and with the other operating parts correspondingly located.

We will now describe the devices of the drawings, reserving it to the claims to point out the novel features and to define the scope of the invention, it being understood that the claims will be given the range of equivalents to which they are entitled.

1 designates the door units or leaves hinged together at their edges 2^a to fold up and extend like a screen and together constituting an accordion door. The first door or the one which is connected with the side of the doorway or other stationary member is a half door and is seen at the left in Fig. 1.

Running lengthwise of both the top and bottom of the doorway are conduits or housings 2 and 3. In the bottom of the upper housing there are located a pair of spaced apart parallel tracks 4. These consist of bars bolted on edge to the depending arms 5^a of brackets or hangers, of which there are a plurality secured by their bases 5^b in spaced apart relation along the top of the doorway. A pair of trolleys 6 run on the tracks and from them are operatively sup-

ported the door-leaves by swivel connections 7 with the middle of the top of said leaves.

Each trolley consists of a cross shaped frame 6^a located vertically between the hanger arms 5^a. 6^b are a pair of studs projecting at right angles from one side of the frame at the ends of the horizontal arm of the cross, said studs rotatably supporting a pair of grooved trolley wheels 8 running on the same track 4. 6^c is another stud projecting from the opposite side of the trolley frame in central location and rotatably supports a third trolley wheel running on the other track. The result is that each trolley 70 has the steadiness against wobbling and tilting of a four wheel support but secures greater compactness. Thus, from the plan view of Fig. 4, it will be seen that the two wheels of the one trolley are on the opposite side or track from the same wheels of the adjacent trolley, with the result that said trolleys are permitted to closely compact together without interfering with the folding up of the doors, which they would do 80 if they had four wheels as relatively large as those shown. The large wheels, of course, have the advantage over the small wheels of rolling much more easily.

Each swivel connection 7 consists of a 85 stirrup 7^a on the bottom of the given trolley frame 6^a. Through the bottom of said stirrup is a vertical hole. The stem of a headed pin 7^b extends loosely down through this hole and then is secured rigidly in any 90 preferred manner in a socket 7^c in the top of the door.

8^a designates lazy tongs which are connected to the door-leaves with the middle pivots of the tongs at the axes about which 95 said individual leaves swivel in opening and closing the accordion door. Thus, the middle pivots at the ends of the tongs consist in the drawings of the pins 7^b already described by which the door-leaves are suspended from the trolleys. Next, the middle pivot intermediate the ends of the tongs consists of a pin 9 projecting vertically in central position from the top of the intermediate door-leaf. Of course, if there were 105 more intermediate door-leaves, the lazy tongs would be increased by the same number of units and the middle pivots of these units would consist of similar pins 9 on the door-leaves. If the increase in the number 110 of leaves should require additional trolleys to support them, then the swivel pins 7^b of

these additional trolleys would be used instead of the pins 9 to operatively connect the lazy tongs to the door-leaves.

The lazy tongs connected as described 5 operate to keep the door-leaves at all times evenly spaced in opening and closing and so prevent jamming of the trolleys on the tracks.

The bottom of each door-leaf has a central 10 stud 10 projecting downwardly through a longitudinal slot in the top of the floor conduit 3. Within the conduit these studs rotatably support rollers 11 which bear against the vertical walls of the conduit when the 15 doors in operation attempt to sway transversely.

Without the lazy tongs, it is impossible to use a floor guide because there is nothing to keep the door-leaves evenly spaced in 20 opening and closing and they inevitably jam because they are confined by guides both above and below. In other words, without the lazy tongs the operation of opening and closing the door-leaves is so irregular and 25 defective that it is impossible to confine or guide said leaves at more than the top. On the other hand, a floor guide can be used conjointly with the lazy tongs, and thereby the great advantage is gained that the doors 30 cannot sway. In short, the lazy tongs and the floor guide work in combination because without the lazy tongs the floor guide cannot be used; and conjointly with the floor guide, the lazy tongs permit the doors to 35 operate without swaying. This prevention of swaying is an important advantage especially in schools where the doors are used to divide up the large assembly rooms into class rooms, and where the tendency is for 40 the children to play with and swing the doors if they can.

The mechanism for operating the accordion door is as follows: The arms 5^a of the endmost hangers operatively support a pair 45 of sprocket wheels 12 over which runs a chain 13 located over the door-leaves when extended and located over their trolley supports. The upper end 6^a of the trolley frame of one or more of the trolleys projects up 50 through one of the links of the chain (Figs. 1 and 3) and is the operating connection between the chain and the door-leaves whereby the travel of the lower stretch of the chain to the left in Fig. 1 folds up the door, and 55 vice versa to the right extends it. The means for operating the chain comprises a hand crank 14 fixed on a shaft 15 projecting rotatably into the hollow wall or casing at the side of the doorway within which it carries 60 a bevel gear 16. In turn there will be and also

within said wall is another bevel gear 17 on the lower end of an upright shaft 18 (supported in suitable bearings not shown) on whose upper end is a bevel gear 19 in mesh with a bevel gear 20 carried on the same shaft as the sprocket wheel 12 (Fig. 5). The result is that turning the handle 14 in one direction or the other operates the chain and doors.

Troughs, rails or guides 21 and 22 are 70 located between the arms 5^a of the hangers and are supported thereby under the upper and lower stretches of the chain 13 to support same from sagging.

Having thus described our invention, 75 what we claim is:

1. In combination with an accordion door, trolleys running on overhead tracks and operatively supporting the leaves of said door, there being two of said tracks in parallel and each trolley having a frame located between the tracks, said frame being the part of the trolley connected with the door and being provided on one side with a pair of wheels running on one of the tracks and 80 on the other side with a single wheel running on the other track, the adjacent trolleys having their wheels disposed oppositely so that the single wheel of one trolley is on the same track as the double wheel of the adjacent trolley.

2. In combination with an accordion door, trolleys running on overhead tracks and operatively supporting the leaves of said door, there being two of said tracks in parallel 85 and each trolley having at least two wheels one on each track but with their centers out of opposition so that one wheel is ahead of the other, thereby adapting adjacent trolleys to compact closely together when the doors 100 fold up.

3. In combination with a foldable door structure, a pair of spaced supporting tracks, relatively movable trolleys mounted on the tracks and having the door structure secured thereto, each of said trolleys comprising a frame, and wheels journaled on the frame and running on the tracks, there being a greater number of wheels on one track than 105 on the other, and the corresponding sets of 110 wheels of the adjacent trolleys operating on different tracks to permit the said trolleys to move into compact overlapping relation.

In testimony whereof we affix our signatures in presence of two witnesses:

WILLIAM H. COOPER,
RICHARD H. COOPER,

Witnesses.
